CLAIM

The ornamental design for a front face of a grill for an electric fan, as shown and described.

DESCRIPTION

FIG. 1 is a perspective view of the front face of a grill for an electric fan of the present design; and, FIG. 2 is a frontal view thereof.

Features shown in broken lines in the drawings are not part of the claim.

The broken line showing of environmental structure in FIGS. 1 and 2 is for illustrative purposes only and forms no part of the claimed design.

The surface(s) or portion(s) of the article not shown in the drawing or described in the specification form(s) no part of the claimed design.
